UNITED STATES PATENT OFFICE

JAMES C. FORBES AND ALBERT W. BANTON, OF EAST CHICAGO, INDIANA, ASSIGNEES
TO O. F. JORDAN COMPANY, OF EAST CHICAGO, INDIANA, A CORPORATION OF
INDIANA

RAILROAD SPREADER

Application filed April 6, 1931. Serial No. 527,872.

This invention relates to improvements in railroad spreaders and it consists of the matters hereinafter described and more particularly pointed out in the appended claims.

5 The invention relates more particularly to means for swinging the main spreader wing away from and in toward the car body and the primary object of the same is to provide a more simple and efficient structure for this 10 purpose and which is so located on the car as to be more easily accessible for inspection and observation.

A further object of the invention is to provide a construction of this kind which includes a power cylinder pivoted at one end to the car and having its piston so pivoted at the opposite end to the wing as to impart movement thereto toward and away from the car, regardless of the angular position the 20 wing happens to be in with respect to its hinge plate on the wing carrying post.

The above mentioned objects of the invention as well as others, together with the several advantages thereof will more fully 25 appear as we proceed with our specification.

In the drawings:—

Fig. 1 is a top plan view of the rear right hand end portion of a railroad spreader embodying our invention.

30 Fig. 2 is a transverse vertical detail sectional view through a part of the spreader, on an enlarged scale and as taken on the line 2—2 of Fig. 1.

Fig. 3 is another detail vertical sectional view through the spreader as taken on the line 3—3 of Fig. 2.

Referring now in detail to that embodiment of the invention illustrated in the accompanying drawings:—1 indicates as a 40 whole, the underframing of a railroad spreader car including the usual side and center sills 2 and 3 respectively, suitably secured together by cross members 4, 5 and 6 as is usual in cars of this kind. At each side 45 of the car and associated with the cross members 4 thereof, is a wing post 7, upon which is mounted for a vertically adjustable movement thereon in any suitable manner, a wing carriage 8 to which a hinge plate 9 is pivoted 50 on a vertical axis 10.

11 indicates the main wing of the spreader as a whole and which wing is pivoted at its inner or front end to the hinge plate 9 by means of a horizontal pin 12. Pivoted to the outer or rear end of said wing is an extension or bank sloping wing 13 of a well known construction. By reason of the construction described, it is apparent that the main spreader wing may be swung away from and in toward the car about the pin 10 as an axis and said wing may be swung relatively to the hinge plate about the pivoted connection 12 into the desired angular position.

Heretofore, in one instance, swinging movement was imparted to the wing away from and toward the car by cylinders carried beneath and extending transversely the framing of the car to the rear of the wing posts. In another instance, said movement was provided by cylinders arranged forward of the posts and connected to arms operating to turn a sleeve on a tubular wing post, while in a third instance, folding braces operated by a shaft alongside the framing were employed for so swinging the wing. Such arrangements have not proven satisfactory for several reasons. In some cases, cost made them impractical, while in others, the operation was not as efficient as was desired.

Our improved wing swinging construction overcomes the objections to those types of wing swinging mechanisms just above mentioned in that it may be made at a much lower cost, may be installed in a position affording the highest operating efficiency and is easily accessible for inspection and is not under the car. Thus, it in no manner interferes with brake rigging and like parts usually carried beneath the car framing.

On the associated cross member 5 where it is connected to the side sill 2, we provide an upstanding bracket 14 having vertically spaced, outwardly extending ears 15 between which one end of a knuckle 16 is pivoted on vertical pin 17. The other end of said knuckle has pivoted thereto by means of a horizontal pin 18, the inner or rear end or head of a cylinder 19. Preferably such an end or head has spaced ears 20 embracing opposite sides of said other end of said

knuckle, the pin 18 passing through said knuckle end and ears.

The cylinder includes a head 21 at its outer or front end, provided with a stuffing box 21^a, through which a piston rod 22 slides. Secured to one end of the rod within the cylinder is a piston 23. To each end or head of the cylinder is connected a conduit 24-25 respectively by which air or other fluid under pressure may be admitted to the desired end of the cylinder to move the piston therein and its rod in the desired direction. Pressure fluid is provided from a tank 26 carried on the car and the inlet and discharge of such fluid to and from the desired end of the cylinder is controlled by a suitable valve 27 also carried on the car. The valve is of such formation that when pressure fluid is admitted to either end of the cylinder, the other end of said cylinder exhausts to atmosphere through said valve.

On the inner or rear side of the wing 11, a suitable distance from the hinge plate 9, we secure a bracket 28 including top and bottom ears 29. Said ears receive between them one end of a knuckle 30 similar to the knuckle before mentioned and said end of the knuckle 30 is pivoted to said ears, by a vertical pin 31. The other end of said knuckle is pivoted by a horizontal pin 32 between the spaced ears of a yoke 33 fixed to the other end of the piston rod 22. The yoke 33 and rod 22 are also capable of a limited relative turning movement. By reason of the knuckle structures mentioned and their pivotal connections with the brackets on the car and wing respectively, a universal joint-like connection is had between the cylinder and car and the piston rod and wing so that swinging movement of the wing in toward or away from the car may be had regardless of the angular position the wing happens to be in.

Associated with the wing for holding it in the desired position into which it has been swung away from the car, we provide a plurality of telescopic braces 34, 35 and 36 respectively. Each holding brace includes inner and outer telescopic brace parts 37 and 38 respectively and the part 37 of each brace is connected by a universal-like joint 39 to the car body framing while the part 38 of each brace is connected by a universal-like joint 40 with the wing 11 and its extension 13. Each brace part 37 carries at its outer end, means 41 for positively locking the associated brace parts in their extended position. As the braces form no particular part of the present invention, other than being associated therewith as described, it is not thought necessary to describe the same in detail. However, it is pointed out that the locking means 41 for the several braces are all fluid pressure ones and are controlled by a valve 42 common to all and located adjacent the valve 27 before mentioned.

In the operation of the construction described, the wing when in a position wherein the car is being transported from one place of use to another, is located in toward and substantially parallel with its associated side of the car. When the wing is in this position, the braces are all reduced in their shortest length as is the cylinder 19 and its rod 22, and the said cylinder is then in a position substantially parallel with and above the side sill 2. When the valve 27 is manipulated to permit the entrance of fluid under pressure to the rear end of the cylinder 19, the piston 23 is forced outwardly as is its rod 22. This will of course, swing the wing 11 about its pivot 10 with the carriage, away from the car and into the desired angular position. As the locking means 41 of the various braces are inoperative at this time, and will permit extension of the braces, this swinging movement of the wing will cause the brace members 38 to slide out or be extended with respect to the brace members 37 to accommodate the position into which the wing has been swung.

After the wing has been swung into the desired position, away from the car, the valve 42 is manipulated so that the means 41 will lock the associated braces in their extended position, to take the thrust of the wing due to its operation upon the material to be spread in the movement of the car. Should it be desired at this time to swing the wing 11 vertically into the desired angular position about its pivot 12, this may be done in any suitable manner, the various universal-like joint connections described for the cylinder, its rod and the braces will readily accommodate such movement.

After the desired spreading operations have been carried out, the several means 41 are caused to release their holding action, after which the valve 27 is actuated to admit pressure fluid to the outer end of the cylinder and to exhaust from the inner end thereof. This will cause a rearward or inward movement of the piston and its rod which will act to draw the wing in toward the side of the car, the braces telescoping to reduce their length so as to also swing in toward the side of the car.

By arranging the wing swinging cylinder as described, it is disposed in that position wherein it in no manner interferes with standard parts beneath the car such as brake rigging and the like. Again, it is in a position wherein it is more easily accessible for inspection and also wherein its maximum efficiency for the swinging of the brace in either direction is attained.

While in describing the invention, we have referred in detail to the form, arrangement and construction of the parts thereof, the same is to be considered as illustrative only so that we do not wish to be limited thereto

except as may be specifically set forth in the appended claims.

We claim as our invention:—

1. A railroad spreader embodying therein a car including a side sill, a spreader wing pivoted at one end with respect to the side of the car for a swinging movement toward and away from the same, fluid pressure means for imparting swinging movement to said wing and including a power cylinder and piston rod disposed in a plane above said side sill, a knuckle pivotally connected to one end of the cylinder in one plane, means extending upwardly from said sill providing a pivotal connection for said knuckle to the car and which connection is arranged in a different plane and means pivotally connecting an end of the piston rod to the wing for swinging movement in more than one plane said connections disposing the cylinder above and substantially parallel with said sill after said cylinder and piston rod operate to swing the wing in toward the side of the car.
2. A railroad spreader embodying therein a car including a side sill, a spreader wing pivoted at one end with respect to the side of the car for a swinging movement toward and away from the same, fluid pressure means for imparting swinging movement to said wing and including a power cylinder and piston rod disposed in a plane above said sill, a knuckle pivotally connected to one end of the cylinder in one plane, means extending upwardly from said sill providing a pivotal connection for said knuckle to the car and which connection is arranged in a different plane, a second knuckle pivotally connected in one plane to the end of the piston rod and means providing a pivotal connection for said second knuckle with the wing and disposed in a plane at an angle to that of said first mentioned pivotal connection therefore said connections disposing the cylinder above and substantially parallel with said side sill after said cylinder and piston rod operate to swing the wing in toward the side of the car.

3. A railroad spreader embodying therein a car body including a side sill, a wing post at one side thereof, a wing pivotally connected with respect to said post for a swinging movement toward and away from the side of the car rearwardly of said post, a power cylinder having at one end a two-way pivotal connection with and above said sill of the car body to the rear of said post, a piston and piston rod associated with said cylinder and means providing a two-way pivotal connection at one end of the piston rod with said wing said connections disposing the cylinder above and substantially parallel with said side sill after said cylinder and piston rod operate to swing the wing in toward the side of the car.
4. A railroad spreader embodying therein,

a car body including a side sill, a main spreader wing pivoted to one side of the car body for a swinging movement away from and toward the same, a bracket rising from said side sill of the car body, a power cylinder having a piston and piston rod associated therewith, means providing a two-way pivotal connection for one end of the cylinder with respect to said bracket and means providing a two-way pivotal connection for the piston rod with said wing said connections disposing the cylinder above and substantially parallel with said side sill after said cylinder and piston rod operate to swing the wing in toward the side of the car.

5. A railroad spreader embodying therein, a car body including a side sill, a main spreader wing pivoted to one side of the car body for a swinging movement away from and toward the same, a bracket rising from said side sill of the car body, a power cylinder having a piston and piston rod associated therewith, a knuckle pivoted in one plane to said bracket and pivoted in another plane to one end of the cylinder, a second knuckle pivoted in one plane to said wing and means providing a second pivotal connection for said second knuckle with the piston rod and which connection is disposed in a plane different from its connections with the wing said connections disposing the cylinder above and substantially parallel with said sill after said cylinder and piston rod operate to swing the wing in toward the side of the car.

In testimony whereof, I have hereunto set my hand, this 1st day of April, 1931.

JAMES C. FORBES.

In testimony whereof, I have hereunto set my hand, this 1st day of April, 1931.
